VAPOR PRESSURE STARTER FOR INTERNAL-COMBUSTION ENGINES

Walter D. Teague, Jr., Alpine, N. J., assignor to
Bendix Aviation Corporation, Teterboro, N. J.,
a corporation of Delaware

Application March 9, 1949, Serial No. 80,543

3 Claims. (Cl. 60—106)

1

This invention relates generally to starting means and methods and to such apparatus and methods including means for starting internal combustion engines for aircraft.

In the starting of certain types of aircraft engines, particularly jet engines, considerable starting power at high speeds is required, and the necessity for using a source of starting energy other than the conventional electric storage batteries has become apparent. Starter systems have been proposed utilizing a fixed charge of stored energy for driving a starter motor, but the problems involved in safely harnessing the suddenly released motive power into sustained cranking of the aircraft engine have necessitated the construction of rugged and bulky equipments and extensive safety precautions in order to safeguard the plane and occupants. Furthermore, the stored energy charge must be sufficient to start the engine under the most adverse conditions which will entail a waste of surplus energy under normal and favorable conditions including of course the problem of safely discharging such surplus energy without permitting the starter mechanism to attain unsafe speeds after being disengaged from the aircraft engine.

One object of the present invention is to provide an effective simple, inexpensive and novel starter system for internal combustion engines.

Another object of the present invention is to provide means for starting internal combustion engines requiring sustained high-speed cranking and to do so by novel, safe and effective means.

Another object of the present invention is to provide a simple novel starter utilizing generated steam for operating the starter motor.

The above and other objects and features of the invention will appear more fully hereinafter from a consideration of the following description taken in connection with the accompanying drawings wherein one embodiment of the invention is illustrated by way of example.

In the drawings, in which like numerals are used to designate the same elements of the several figures:

Fig. 1 shows a schematic view of the novel starter system of the present invention.

Fig. 2 shows an enlarged view of fan and fuel nozzle assembly of Fig. 1.

Fig. 3 shows a wiring diagram for controlling the operation of the starter system of Fig. 1.

In Fig. 1 the starter system is shown as comprising in general a steam generator 10, a source of fuel 12 and means for transferring fuel from

2

the source to the steam generator shown as a fuel pump 14, a steam operable starter engine 16 operated from steam generated in the steam generator, means in the steam generator for igniting the fuel in the form of a spark plug 18, and means for directing the burning gases over the steam generator heating surfaces shown as a fan 20, including means for controlling the proper operation of the various components of the 10 starter such as the thermostat chamber 22 and control box 24.

The steam generator is illustrated as a water tube boiler 10 but steam may of course be generated in any number of ways well known in the 15 art without departing from the scope of this invention. Fuel enters fuel nozzle 26 through the hollow fan shaft 28 (Fig. 2) from pipe 30 leading from fuel pump 32 and fuel tank 34. The 20 operation of the fuel pump is controlled from control box 24. To adjust the pressure and amount of fuel entering the fuel nozzle a pressure regulator 38 and check valve 40 are connected in pipe 30. The steam generator or boiler 10 comprises a boiler housing 42 and spirally coiled water tubes 44 and 46. Surrounding the water tubes are 25 wall portions 48 and 50 forming a tempering water tank or jacket 52 and air preheat chamber 54, respectively. The water tank is filled through a filler pipe 53 which is provided with a safety pressure and vacuum relief valve 55. Mounted on top of the boiler is a fan motor 56 driving a fan or blower 20 through the hollow fan shaft 28 adapted to rotate within a tubular sleeve 58 formed integrally with or welded to boiler housing 42. Sleeve 58 is provided with a bore adapted 30 to connect with fuel pipe 30 and fuel passes from the pipe into the sleeve, through openings 60 in the wall of the hollow shaft 28 to a fuel nozzle 26 which is in the form of a disc having circumferentially spaced radial outlet holes 61. With the fan motor running at constant speed and the fuel pressure constant, the force with which the fuel leaves the fuel nozzle outlets will depend on the diameter of the nozzle disc. The disc is 35 movably mounted on the fan shaft and may readily be changed to suit the requirements of the particular fuel used. The fan shaft 28 is sealed relative to the sleeve 58 on both sides of the fuel inlet in order to prevent fuel from escaping between the sleeve and shaft. Air enters air preheat chamber 54 through air inlet openings 62 and is forced into the combustion chamber 64 by the fan 20 and mixed with the fuel flowing from nozzle 60 and the fuel mixture is ignited from 40 spark plug 18. The combustion takes place in

the chamber 64 and the burning gases are forced in between and in close contact with the water tubes on their way out through the exhaust flue 66. The water tube boiler shown is of a semi-flash type in which a single pass tube receives fluid at the bottom thereof from the water pump 68 and passes it through the spirally arranged coils 44 to the superheater coils 46 which form a coil closely adjacent to the inner surface of the wall of the combustion chamber, before it passes 10 the superheated steam through pipe 70 leading to thermostat chamber 22. From the thermostat chamber the steam passes through a pressure safety valve 72 to a starter motor 16 which is shown as a vane-type engine but may of course be of any suitable type such as a steam turbine or reciprocating engine. The vane-type engine shown is lubricated from oiler 14 placed in the steam line and which passes off sufficient lubrication to 15 keep the engine properly lubricated. Mounted on the motor shaft is a normally closed centrifugal switch 76 which opens when the engine reaches a certain predetermined speed, in this type of installation usually approximately 5000 R. P. M. at which speed it is safe to assume that the aircraft 20 engine has fired and is able to continue under its own power.

Water is stored in the water jacket 52 and is pumped into the boiler by the water pump 68. A by-pass valve 80 actuated by and connected 25 to a bulb located in the thermostat chamber 22 by a tube 82 and by means of fluid expansion in the bulb it opens or closes the valve in response to steam outlet temperature. With the valve in closed position the water pump 69 is pumping 30 water directly into the boiler tubing and in fully open position it allows the pump outlet to bypass back to the inlet thus merely circulating water through the pump. A check valve built integrally with the by-pass valve prevents boiler 35 pressure from forcing boiler water back to the tank when the latter valve is fully open.

A cool-off switch 84 is mounted on the exhaust flue and connected to the blower fan motor, the purpose of which will be apparent as the description proceeds.

High temperature switch 86 is controlled by another bulb in thermostat chamber 22 and connected thereto by a tubing 88. The high temperature switch is normally closed and connected 40 in series with centrifugal switch 76.

The operation of the system will be better understood by referring to Fig. 3 in which the electrical control of the system is schematically outlined. A source of electromotive force 90 such 45 as a storage battery is shown as being connected to one terminal of main switch 92 shown as a simple toggle switch in closed position. The other terminal of switch 92 is connected to one side of a push button switch 94 and to a bus 96 50 connected to one common side of multiple contact switch 98 arranged to be closed by relay 100, contact 102 serving to hold the relay 100 in closed position after starter button is released. The relay 100 is connected to ground through 55 high temperature switch 86 and centrifugal switch 76. Contact 103 actuated with contact 102 connects water pump 68, fuel pump 14, fan 20 and through booster coil 104 spark plug 18 to the source 90. Cool-off switch 84 is normally 60 open but is closed when the exhaust gases reach a predetermined temperature and opens up again as the temperature sinks below this value and is connected between bus 96 and the input to fan 20. The water pump 68, the fuel pump 14, the 75

fan 20 and the booster coil 104 are shown as being connected to the same contact 103 but it may be found advantageous to connect some or all of them to separate contacts.

The operation of the starter system is as follows:

The main switch 92 is closed and starter button 94 is depressed to close relay 100 and thereby close contacts 102 and 103. When the starter button is released the relay will remain closed by the holding contact 102 which permits current to flow through the relay coil 100, the normally closed high temperature switch 86 and centrifugal switch 76 to ground. The closing of the relay 100 will also close contact 103 and energize water pump 68, fuel pump 14, fan 20 and spark plug 18. The fuel pump 14 will pump fuel from the fuel tank 12 through pipe 38, pressure regulator 38, check valve 40 and hollow fan shaft 78 to the rotating nozzle 26. The fuel entering through the nozzle outlet holes 61 is mixed with air drawn from the air preheat chamber 54 by the rotating fan 20. The fuel-air mixture is ignited by spark plug 18 and the burning gases are forced over the water coils 44 and 46 through the exhaust outlet 66. While the boiler is building up steam pressure water pump 68 is merely circulating water by the action of the by-pass valve 80. The generated steam is supplied to the starter engine 16 which begins to crank the aircraft engine as soon as the steam pressure builds up to a value sufficient to overcome the resistance of the engine to turning. The starter engine shown for the sake of illustration is a vane-type engine permanently engaged to the aircraft engine although piston or turbine steam engines, in and of themselves well known in the art, may of course be used, in which case it may be necessary to provide means for disengaging the starter from the aircraft engine such as by a jaw advancing-retracting mechanism or by an overrunning clutch. The system is protected against excessive steam pressure as by a safety valve 72 in the steam supply line and against excessive temperatures of the steam which may arise under abnormal operating conditions such as failure of the water supply, by high temperature switch 86. The high temperature switch 86 is normally closed but will open in response to a temperature responsive element such as a fluid filled bulb exposed to the steam in thermostat chamber 22. When this switch 86 opens, the holding circuit for relay 100 will be interrupted and the system will shut off with the opening of contacts 102 and 103.

When the steam temperature approaches a certain value, indicating that the water in the boiler tubes is getting low, by-pass valve 80 will admit water to the boiler in an amount depending on the temperature of the steam. Thus, when the steam temperature reaches a certain predetermined value, the by-pass valve will gradually open thereby permitting water pump 68 which up to this time has merely been circulating water from its output to its input through the by-pass valve, to force water into the boiler from the water tempering tank 52. If the steam temperature continues to rise, the by-pass valve will continue to open until the pump is pumping water into the boiler at full capacity. A drop in temperature will cause a corresponding decrease of water supplied to the boiler. If the steam temperature for some reason continues to rise, this indicates a fault in the system and will cause a shut down thereof by the action of high

temperature switch 86 as previously explained. Pressure relief valve 72 will prevent dangerous steam pressure from building up in the system if the aircraft engine should abnormally resist cranking.

When the starter engine has attained a speed at which it is safe to assume that the aircraft engine has fired and is able to continue under its own power, the centrifugal switch 76 opens and thereby interrupts the holding circuit for relay 100 which causes contacts 102 and 103 to open thereby shutting off the system. In order to expel all the burning gases, there is provided a cool-off switch 84 which is adapted to close when the exhaust temperature reaches a predetermined value, and thereby connects the fan motor directly to the main bus 98. When the system is shut off and contacts 102 and 103 have opened, the fan will continue to run until the exhaust temperature falls to a temperature sufficiently low to open the cool-off switch 84 thereby shutting the fan off.

In the illustration of the preferred embodiment of this invention, the system is shown as operating a single starter engine while of course the system may be located anywhere in the plane and may be used to start all the engines in a multi-engine plane. In the system described, water is used but, of course, any suitable fluid may be used to produce the pressure necessary to operate the starter engine and other suitable means for producing such pressure well known in the art may be utilized without departing from the scope of my invention.

Although only one embodiment of the invention has been illustrated and described, various changes in the form and relative arrangements of the parts may be made to suit requirements.

What is claimed is:

1. A starter system for internal combustion engines comprising, a starter motor, a vapor generator for producing vapor under pressure to drive said motor including a combustion chamber and exhaust means therefor and fluid containing means having inlet and outlet means and having surfaces in heat exchanging relationship with said combustion chamber, means supplying fluid to said fluid containing means, means for introducing a combustible mixture into said combustion chamber, means for igniting said combustible mixture, means for forcing the combustion products over said heat exchanging surfaces and out said exhaust means, temperature responsive switch means adjacent said exhaust means, control circuit including circuit closing means energizing said combustible mixture introducing means, ignition means, forcing means and supply means, means for deenergizing said circuit if vapor attains a predetermined temperature, and means for deenergizing said circuit upon said motor reaching a predetermined speed, and said temperature responsive switching means being adjacent said exhaust means for maintaining said forcing means in operation after the deenergization of said circuit until the temperature of said exhaust means has dropped to a predetermined safe temperature.

2. In a starter system for an internal combustion engine comprising a starter engine, a vapor generator for driving said engine and having a combustion chamber including exhaust means, and fluid containing means having inlet and

outlet and having surfaces in heat-exchanging relationship with said combustion chamber means for supplying fluid to said inlet of said fluid containing means, means for introducing a combustible mixture into said combustion chamber, means for igniting said mixture, and means for forcing the combustion products over and between said heat-exchanging surfaces and out said exhaust means; the combination of a control circuit for said system comprising a circuit closing means setting in operation said means for supplying fluid to said inlet of said fluid containing means, said means for introducing a combustible mixture into said combustion chamber, said combustion product forcing means, and said ignition means; and means for opening said circuit closing means when the starter engine to be started reaches a predetermined speed; and means responsive to the temperature of said exhaust gases for maintaining said means for forcing said combustion products in operation until the temperature of said exhaust gases has fallen to a relatively low value.

3. For use in a vapor pressure motor starting system for internal combustion engines; a vapor generator for producing vapor under pressure to drive said motor comprising a combustion chamber and exhaust means therefor, fluid containing means having inlet and outlet means and having surfaces in heat exchanging relationship with said combustion chamber, means to supply fluid to said fluid containing means, means for introducing a combustible mixture into said combustion chamber, means for igniting said mixture, fan means for forcing the combustion products over said heat exchanging surfaces and out said exhaust means, temperature responsive switch means adjacent said exhaust means, a control circuit including circuit closing means for energizing said combustible mixture introducing means, ignition means, fan means and supply means, means for deenergizing said circuit upon said vapor attaining a predetermined temperature, means for deenergizing said circuit upon said motor reaching a predetermined speed, and temperature responsive switching means adjacent said exhaust means for maintaining said fan means in operation after deenergization of said circuit until the temperature of said exhaust means has dropped below a predetermined temperature.
